United States Patent Office

Des. 175,500
Patented Sept. 6, 1955

175,500

LADY'S SHOE OR SIMILAR ARTICLE

Jules Fern, Los Angeles, Calif., assignor to Fern Shoe Company, Los Angeles, Calif., a corporation of California

Application September 3, 1954, Serial No. 32,152

Term of patent 3½ years

(Cl. D7—7)

Fig. 2 is a plan view thereof;

Fig. 3 is a longitudinal sectional view thereof; and

Fig. 4 is a front elevation thereof.

I claim:

The ornamental design for a lady's shoe or similar article, substantially as shown.
